(57) **CLAIM**

The ornamental design for a bent frame paint roller assembly, as shown and described.

DESCRIPTION

FIG. 1 is a perspective view of a bent frame paint roller assembly showing our new design;

FIG. 2 is a first side view thereof;

FIG. 3 is a second side view thereof;

FIG. 4 is a back view thereof;

FIG. 5 is a front view thereof;

FIG. 6 is a top side view thereof; and,

FIG. 7 is a bottom side view thereof.

The broken lines illustrate portions of a bent frame paint roller assembly that form no part of the claimed design.

1 Claim, 5 Drawing Sheets
